(57) **CLAIM**

The ornamental design for a concrete table, as shown and described.

DESCRIPTION

FIG. 1 is a perspective view of a concrete table.

FIG. 2 is a top view of the concrete table of FIG. 1.

FIG. 3 is a bottom view of the concrete table of FIG. 1.

FIG. 4 is a left side view of the concrete table of FIG. 1.

FIG. 5 is a right side view of the concrete table of FIG. 1.

FIG. 6 is a back view of the concrete table of FIG. 1.

FIG. 7 is a front view of the concrete table of FIG. 1; and,
FIG. 8 is a perspective view of a concrete table of FIG. 1 with
the top raised to show an exemplary block arrangement
underneath the raised top.

The broken lines are for environmental purposes only and
form no part of the claimed design.
